TO MOHAWK CARPET MILLS, INC., OF AMSTERDAM, NEW YORK, A CORPORATION
OF NEW YORK.

SPOOL BEARING FOR TUBE FRAMES.

Application filed September 27, 1923. Serial No. 665,192.

To all whom it may concern:

Be it known that we, DANIEL S. MUNN and GEORGE CROSSLAND, citizens of the United States, and residents of Amsterdam, county of Montgomery, State of New York, have invented certain new and useful Improvements in Spool Bearings for Tube Frames, of which the following is a specification.

10 This invention relates to suspension hangers for tube frames and is intended to provide such a device with a yarn spool bearing that will be completely reliable for the purpose of retaining the spool-journal in position for rotation as the yarn is drawn off the spool to supply the tufts for weaving, while permitting the easy and quick removal of the spool from its bearing for yarn-receiving or other purposes, while involving no endwise stress upon or displacement of the spool.

While it has been proposed to use a spring bearing arm that can be sprung outward far enough to clear the end of the journal, such devices are not rigid enough to remain in proper spool-holding position after they have been flexed a number of times and, moreover, they can not be released while the tube frame is supported in the transfer mechanism by which the yarn is presented to the fabric being woven in the loom, since the hook-arm is then in its innermost position and would prevent the necessary outward movement of the spool bearing arm.

35 The present invention makes possible the use of a rigid spool-supporting arm or member not subject to easy distortion or displacement while securing the retention of the journal therein by positively locked retaining means which, by its construction and arrangement, may be instantly released by the operator to permit removal of the spool.

The invention comprises a suspension hanger provided with a spool-bearing arm or member having an open bearing for the spool journal and a movable keeper so constructed and arranged as to automatically and positively lock itself to the bearing member when moved to operative or journal-retaining position, while being releasable therefrom merely by application of lateral pressure in the act of opening the bearing for removal of the spool.

By reason of the construction employed there is no need of using any accessory spring detent, bolt or the like to retain the keeper in place yet it is so positively held against unlocking that no accidental pressure or blow exerted in the direction of the movement of the keeper away from the spool journal tends to release it.

These and other features of the invention will be explained in detail in the following portion of the specification and will be defined in the claims hereto annexed.

In the accompanying drawings is illustrated a preferred form of construction and arrangement illustrative of the application of the principles of this invention, in which:

Figure 1 is a front elevation of a tube frame for tuft weaving with the middle portion of the spool and carrier bar broken away, the spool-bearing member being shown partly in vertical section.

Figure 2 is an end elevation of the suspension hanger with our improved bearing construction with the carrier bar shown in cross section.

Figure 3 is a plan view of the suspension hanger equipped with our improvement.

Figure 4 is a detail view showing the journal-retaining member in perspective.

In the drawings, the improved bearing construction is shown applied to a form of tube frame now in commercial use comprising generally a longitudinal tubular carrier bar 10, secured at its opposite end to suspension hangers each of which comprises a vertical hanger arm 1, whose upper end is outwardly offset as shown at 2, and projects upward to form a chain-penetrating extension 3, cooperating with a hook arm 4, which is provided at its upper end with a chain-engaging hook 5, and which is fulcrumed at its lower end upon a fulcrum pin 7 which is partly embraced by a reversely bent hook portion 6, formed at the lower end of the hook arm. The hanger is secured firmly to the tubular carrier bar by means of a U-shaped attaching bracket whose upper and lower arms 8, telescope inside of the open end of the carrier bar, and whose middle portion is secured to the suspension hanger by rivets or the like. These features, however, form no part of the present invention and are shown merely for the purpose of making clear the relation of the

bearing to the other parts of the suspension hanger of the tube frame.

The spool-bearing arm or member 11, is located on the inner face of the hanger arm 2, to which it is rigidly secured and extends upward to form a bearing support for the spool-journal 9^a, of the yarn-carrier spool 9. The spool-bearing arm 12, at the other end of the spool, may be of usual construction to receive the opposite journal 9^a, of the yarn-spool.

The spool-bearing arm 11, is provided at its upper end with a vertical notch 11^a which is preferably of greater depth than the diameter of the spool-journal, and forms an open bearing from which the spool-journal may be removed by merely lifting the latter from its seat therein which permits the withdrawal of the opposite journal 9^a, from the usual closed bearing in the spool-bearing arm 12.

The open bearing 11^a, facilitates a quick removal of the spool from its bearings but, obviously, makes it possible for the spool to drop out when the tube frame is inverted in the course of its travel toward or away from operative position by means of its carrier chains, from which it is suspended by means of the suspension arms 1 and 4. To prevent such accidental displacement we have devised a special construction and arrangement for positively retaining the spool-journal 9^a in its open bearing 11^a. The device employed for this purpose, as shown in the drawings, comprises a pivotal hook or latch 15, fulcrumed upon a pivot stud 16, secured to the suspension hanger near the carrier bar and movable forward and back so that its upward extension 15^a, will overhang the spool-journal 9^a, when the keeper is in locked or operative position, since the lower edge 15^b of the upward extension 15^a serves to engage the spool-journal and in effect closes the open bearing.

This keeper is preferably made of sheet steel and has a portion adjacent to the edge 15^b, turned outwardly to form a projecting lug or lip 15^c, which, as shown best in Figure 4, is inclined forwardly to a thin or narrower edge or point but terminates at its rear end in an abrupt shoulder. The interlocking projection 15^c, in the form shown in the drawings, is shorter than the width of the open bearing or notch 11^a, so that this locking member or lip may spring into engagement with the inside edge of the open bearing so as to project therethrough with its abrupt shoulder overlapping the rear vertical edge of said slot or bearing. While the pressed steel piece 15, is fairly stiff, nevertheless, it is capable of swinging inwardly sufficiently when pressed forward with its inclined projection 15^a riding against the inside face of the bearing member 11, to allow the shoulder to pass by the

rear wall of the open bearing when the inherent elasticity of the keeper causes it to spring back against the inside face of the bearing member 11, with its projecting lip extending into the open bearing or slot.

It will be seen, therefore, that the very act of pushing the keeper forward to journal-retaining position results in automatically and positively interlocking the keeper and the spool-bearing member or bracket together when the keeper is in operative journal-retaining position. On the other hand, all that the operator is required to do, when opening the bearing to remove the spool, is to press inwardly on the upper end or tongue 15^a, of the keeper which is made conveniently long for just this purpose, thereby springing the locking member inwardly out of engagement with the notch or open bearing and allowing it to move easily backward out of the path of the spool-journal.

The arrangement is such that the keeper can be locked or unlocked without regard to the position of the hook arm 4, so that the spool can be removed at any stage desired. A blow or pressure in the direction that would swing the keeper backward to open position would be positively resisted by the positive locking engagement between the shoulder and the cooperating edge of the bearing bracket. The keeper is protected against inward pressure by the outside portions of the suspension hanger so that the described arrangement makes a very secure and reliable means for retaining the bearing spool in place, while at the same time affording a device for this purpose which can be instantly released by the use of only one hand of the operator, thereby leaving the other hand free to grasp the spool or other part of the tube frame.

The shoulder 15^c presents a smooth bearing surface to the upper side of the journal instead of opposing the raw or cut edge of the metal to resist the upward thrust of the journal.

What we claim is:

1. A spool bearing bracket for a tuft tube frame embracing in its construction an upright bearing arm formed at its upper end with an upwardly opening bearing recess whose side and bottom edges afford bearing support for an inserted spool journal, a keeper pivotally mounted to swing into position to overhang such inserted journal and provide a retaining bearing over the top of the journal to prevent escape of the journal upward, the pivotal axis of the keeper being disposed diametrically opposite the open side of the bearing to prevent the upward thrust of the journal from exerting pressure against the keeper in a direction tending to cause the keeper to move to journal-releasing position, said keeper being formed with a lateral projection ar-

ranged to engage an edge of the open bearing to prevent accidental displacement, substantially as described.

2. A spool bearing bracket for a tuft tube frame, embracing an upright bearing arm slotted downwardly from its upper end to form an upwardly opening bearing recess for a spool journal, a keeper mounted upon the lateral face of said arm by a pivotal connection, said keeper being formed at its upper end with a hook adapted to overhang an inserted journal to receive the upward thrust of such journal, said hook being provided with a lateral wedge shaped projection whose sloping side tends to spring the keeper away from the bearing arm when being moved to locking position and whose abrupt side forms a locking engagement with the side edge of the bearing recess when the keeper overhangs the journal, substantially as described.

3. A spool bearing bracket for a tuft tube frame embracing in its construction an upright spool bearing arm provided at its upper end with an open bearing recess, a pivotal keeper having one side edge cut away to form a journal-engaging edge arranged to overhang a journal inserted in said bearing, said edge being formed with a lateral projection to engage an interior edge of the bearing recess to lock the keeper against displacement, a portion above said journal-engaging edge being extended above the end of the bearing arm to provide a finger hold for shifting the keeper into and out of locking engagement with the bearing arm, substantially as described.

In witness whereof, we have subscribed the above specification.

DANIEL S. MUNN.
GEORGE CROSSLAND.
